(57) **CLAIM**

The ornamental design for a solar powered light fixture, as shown and described.

DESCRIPTION

FIG. 1 is a front elevation view of the solar powered light fixture showing a first embodiment of my new design, the rear view being a mirror image thereof;

FIG. 2 is another front elevation of the design of FIG. 1 showing a first alternate edge on the translucent shade in broken lines;

FIG. 3 is another front elevation of the design of FIG. 1 showing a second alternate edge on the translucent shade in broken lines;

FIG. 4 is an exploded perspective view thereof;

FIG. 5 is an exploded perspective view of the solar powered light fixture showing a second embodiment of my new design;

FIG. 6 is front elevation of the design of FIG. 5 showing a first alternate edge on the translucent shade in broken lines;

FIG. 7 is front elevation of the design of FIG. 5, the rear view being a mirror image thereof;

FIG. 8 is a front elevation of the design of FIG. 5 showing a second alternate edge on the translucent shade in broken lines; and,

FIG. 9 is an enlarged top plan view of both embodiments thereof.

The broken lines shown on the drawings depict portions of the solar powered light fixture that form no part of the claimed design.
